UNITED STATES PATENT OFFICE.

WILLIAM S. BRAWNER, OF ST. LOUIS, MISSOURI.

LINIMENT.

SPECIFICATION forming part of Letters Patent No. 320,041, dated June 16, 1885.

Application filed May 31, 1884. (No specimens.)

To all whom it may concern:

Be it known that I, WILLIAM S. BRAWNER, of the city of St. Louis, in the State of Missouri, have invented a certain new and useful 5 Composition of Matter or Liniment to be Used in the Treatment of Rheumatism, &c., of which the following is a specification.

My composition consists of the following ingredients, combined in the proportions 10 stated, viz: lard, four pounds; red-cedar chips, two ounces; saltpeter, three ounces; salt, two ounces; spirits of turpentine, two ounces; tincture of pennyroyal, six drams. All of the ingredients, with the exception of the penny- 15 royal, are boiled together for about three-fourths of an hour, then strained and the pennyroyal added, and bottled for use after it has

been thoroughly mixed. The heated mixture should be allowed to cool somewhat before the pennyroyal is added.

In using the above-named composition it should be applied to the affected part by considerable friction with the hand.

What I claim, and desire to secure by Letters Patent of the United States, is—

The herein-described liniment or salve, which consists in a composition produced by the mixture of lard, red-cedar chips, saltpeter, salt, spirits of turpentine, and tincture of pennyroyal in about the proportions named.

WILLIAM S. BRAWNER.
